UNITED STATES PATENT OFFICE.

JOSEPH LACROIX AND JOSEPH DESAUTELS, OF FALL RIVER, MASSACHUSETTS, AS-SIGNORS OF ONE-THIRD TO SAID LACROIX, ONE-THIRD TO SAID DESAUTELS, AND ONE-THIRD TO CHARLES J. BURDICK, OF PROVIDENCE, RHODE ISLAND.

SPINNING-MACHINE.

1,071,061.

Specification of Letters Patent.

Patented Aug. 26, 1913.

Application filed September 12, 1910. Serial No. 581,497.

To all whom it may concern:

Be it known that we, JOSEPH LACROIX and JOSEPH DESAUTELS, citizens of the United States, residing at Fall River, in the county 5 of Bristol and State of Massachusetts, have invented a new and useful Improvement in Spinning-Machines, of which the following is a specification.

This invention relates to certain new and 10 useful improvements in spinning machines and more particularly to twisting frames and the like with special reference to wet twisting. In wet twisting a great deal of difficulty has been experienced on account 15 of the spotting or discoloration of the thread. This has been due to several causes. In the first place the thread sliver in running from the water trough has carried an excess of water which has spattered 20 the adjacent parts of the frame causing an increase in the gathering of dirt adjacent to the run of the thread, and also wetting the floor and causing decay as well as spattering the twisted thread as it is wound. 25 Aside from this general spattering there is the further difficulty which has arisen from the relation of the feed rolls to the water trough. When these rolls had been located in front of the water trough, as has been 30 the usual practice, the thread has been badly spotted on account of the forming of verdigris on the rolls where they have been of brass and on account of the collection of oil, dust and other dirt both from the air 35 and from the water trough. When the rolls have been located behind the trough, the thread has been discolored by the entwining of that sediment which unavoidably gathers in the trough by the running back of the 40 twist into the trough. This running back of the twist into the trough caused further difficulties because the twisted thread did not absorb the water as rapidly so as to become uniformly moistened as did the un- 45 twisted sliver. To overcome these difficulties we have devised our present invention in which we have located the feed rolls at the rear of the water trough and have provided means for stripping the water from 50 the thread and also for preventing the back twist of the thread from entering the trough.

In the drawings, we have shown such a portion of a twisting frame as is necessary

to illustrate our invention, the parts of 55 which are indicated by reference numerals, similarly employed in the specification which follows.

In the drawings: Figure 1 is a side elevation partly in section of such parts of a 60 twisting frame as are involved in our invention, and Fig. 2 is a fragmentary side elevation of the roll member over which the thread runs in leaving the trough.

The tension feed rolls 1 and 2 are supported in a suitable bracket 3 to feed a thread α to the water trough 4. The rolls 1 and 2 draw the thread from spools (not shown) through the eye 5. The trough 4 is suitably supported on the bed 6 and side 70 support 7.

Within the trough 4 is disposed a submerged glass tube 8 extending lengthwise of the trough and carried by suitable brackets 9. At the top of the trough and just inside 75 of its outer edge is a guide rail 10 of porcelain or like material formed of somewhat inverted V-shape in cross section and having a series of spaced notches 11 along its upper edge. These notches provide guides 80 for the thread which strip the water from the thread as it arises from the trough and allows the water to run back within the trough. The notches also form checks for any back twist which may work up in the 85 thread α from the twisters to which the thread passes through the guide eye 11'.

The thread is drawn from the spools through the eye 5, under the tension roll 2 and over the tension roll 1, then passing 90 down enters the water, passing under the glass rod 8, and emerges from the water and passes through one of the notches 11 on the rail 10, thence through the guide eye 11' to the spinning ring (not shown).

A guiding support for the thread is provided at 12 mounted on the side supports 7 and acting to prevent the thread from becoming engaged with the sharp edges of the trough 4 or the support 7. It will be seen 100 that the tension rolls 1 and 2 which are mounted at the rear of the water trough are kept dry and will not collect oil or dirt from the trough or from verdigris. The thread is thus kept clean and unspotted.

Should the thread break while under tension it may be spliced while still dry. It will also be evident to those skilled in the

art that by leading the thread *a* directly from the feed roll 1 to the rail 10 (as indicated by the dotted line *a'* in Fig. 1) dry twisting may be accomplished on this machine, either in whole or in part.

Having thus described our invention, what we claim as new and desire to secure by Letters Patent is—

1. In a twisting frame, a spool support, a trough, feed rolls located between said spool support and said trough, a guide within said trough under which the thread passes from the feed rolls, a drip rail located within the edge of said trough, a check on said rail over which the thread passes from said guide, and a twisting device adjacent to said trough to which said thread passes directly from said check, substantially as described.
2. In a twisting frame a spool support, a trough, feed rolls located between said spool support and said trough, a guide within said

trough under which the thread passes from the feed rolls, a notched check located within the edge of said trough over which the thread passes on leaving the trough, and a twisting device adjacent to said trough to which the thread passes directly from said check, substantially as described.

3. In a twisting frame the combination of a water trough, a notched check located within the edge of said water trough and a twisting device adjacent to said trough to which the thread passes directly from said check.

In testimony whereof we have signed our names to this specification in the presence of two subscribing witnesses.

JOSEPH LACROIX.
JOSEPH DESAUTELS.
